BLOWER-FILTER UNIT

Gerald L. Schwarz, Cleveland Heights, Ohio, assignor to Air Controls, Inc., Cleveland, Ohio, a corporation of Ohio

Application March 18, 1950, Serial No. 150,499

3 Claims. (Cl. 230—114)

11

This invention relates to a plug-in type blower filter unit adapted to be used as a furnace booster, a window ventilator, and as an evaporative cooler.

In carrying out my invention a square-sided blower is provided, having a casing wrapped around and secured to the sides of the blower, thereby eliminating the use of the conventional scroll sheet.

An object of the invention is, to provide a combination blower-filter unit adapted to be selectively used as a furnace booster, a window unit or as an evaporative cooler.

Other objects are to provide a relatively small compact blower filter unit of the type ordinarily used on windows, having several times the air moving capacity of conventional units now in operation.

Another object is to provide a design eliminating the use of a conventional scroll sheet by providing a casing wrapped around the periphery of the two square blower sides, such casing extending far enough on one side to cover the motor and driving unit and the filter means and on the other side far enough to cover the bearings, brackets, shaft and a second filter means.

Other objects are to provide a compact, readily accessible blower-filter unit, which may be quickly and easily installed on various air moving units, said unit functioning to move large volumes of air at a relatively low cost.

These and other objects will be apparent during the course of the following specification.

In the drawings forming a part of this specification Fig. 1 is a perspective view of an illustrative embodiment of my invention, with parts broken away: while

Fig. 2 is an end view with the filter removed.

The device comprises two parallel side walls 11 and 12, while a casing 13, extending around the edges of the walls 11 and 12, is suitably secured to flanges on the wall edges by rivets and extends a sufficient distance beyond the wall 11 to provide a housing 14, and on the opposite side the casing extends a relative shorter distance beyond the wall 12. An electric motor 15, operatively connected to a sheave 16 by means of a V belt 17, is mounted in the housing 14.

An air impeller 18 comprises a series of blades 19 having their ends suitably mounted in circular end plates 20, each secured to a cooperating spoke 20 (a) and carried by hubs 20 (b), said hubs being journaled in bearings 22 supported by arms 24, suitably secured to their respective side walls 11 and 12. Oil tubes 26 mounted in said arms are provided at the top unit with re-

2

movable caps 27 which may be removed when oil is to be supplied to bearings 22 through oil tube 26. The sheave 16 is rotatively mounted on shafts 28. The V belt 17 connecting the motor 15 and sheave 16, serves to drive the impeller 18 in an obvious manner.

As shown in Fig. 1 filter means 29 comprising a flat piece of spun glass or other suitable filter material is adapted to be disposed at the sides 11 and 12 of the device by engaging the end portions thereof within the peripheral flange 30 suitably secured to the margin of the housing 14.

A similar filter means at the opposite side of the device is similarly mounted. The filter 29 may be quickly and easily removed by bending it and unseating it from its engagement with the flange 30. The vertical position of the motor 15 may be regulated in an obvious manner by turning thumb screw 31. A variable cut-off device, shown in Fig. 1 comprises plate 32, adapted to be raised and lowered to vary the pressure and volumetric characteristics of the air issuing therefrom.

25 In operation air is drawn into the sides through the filters 29 by rotation of the impeller 18, and is forced out through outlet opening 33 as will be readily apparent. The device described herein may be installed in a residence furnace in the winter and then in the summertime may be readily removed and installed in a window to circulate fresh air. Evaporative cooling means may be added by providing a trickle of cold water down through the filters 29. Aspen wood filters may be used for such purpose and would provide humidification means. The water for such operation may be provided by having a flat pan of water at the top of the casing 14 with a suitable flow level valve and holes drilled through the filters.

40 When the device is used in a furnace a thermal switch may be inserted in the furnace bonnet, thereby providing an automatic furnace blower-filter unit readily installed by the furnace user himself, without the assistance of a skilled furnace man.

45 It will be apparent to those skilled in the art
that my invention may be variously changed
used or modified, without departing from the
spirit of the invention or sacrificing the advan-
50 tages thereof, and that the present embodiment of
my invention is illustrative only, and that my
invention is not limited thereto.

vention

- 1 claim.

1. A blower-filter device comprising, a casing 55 including a pair of spaced side walls and a con-

tinuous casing wall extending around the edges of said side walls forming the front, back, top and bottom walls of said device, a motor mounted on said bottom wall outside one side wall, the side walls being provided with aligned air inlet openings disposed above the upper margin of said motor, one of said casing walls being provided with an air outlet opening, an air impeller revolving on a horizontal axis, aligned with said side wall openings and supported by said side walls, the disposition and arrangement of the parts of said device being such that rotation of said impeller draws air in a straight unobstructed course through both said side wall openings into the interior of said impeller and forces it outwardly through said outlet opening.

2. A blower-filter device comprising, a casing including a pair of spaced side walls and a continuous casing wall extending around the edges of said side walls forming the front, back, top and bottom walls of said device, the continuous casing extending beyond one of said side walls forming a motor housing, a motor mounted on said bottom wall, said side walls being provided with aligned air inlet openings disposed above the upper margin of said motor, one of said casing walls being provided with an air outlet opening, an air impeller revolving on a horizontal axis, aligned with said side wall openings, and supported on said side walls, the disposition and arrangement of the parts of said device being such that rotation of said impeller draws air in a straight unobstructed course through both said side wall openings into the interior of said impeller and forces it outwardly through said outlet opening.

3. A blower-filter device comprising, a casing including a pair of spaced side walls and a continuous casing wall extending around the edges of said side walls forming the front, back, top and bottom walls of said device, the continuous casing extending beyond one of said side walls forming a motor housing, a motor mounted on said bottom wall, means for varying the position of said motor, said side walls being provided with aligned air inlet openings disposed above the upper margin of said motor, one of said casing walls being provided with an air outlet opening, an air impeller revolving on a horizontal axis, aligned with said side wall openings, and supported on said side walls, the disposition and arrangement of the parts of said device being such that rotation of said impeller draws air in a straight unobstructed course through both said side wall openings into the interior of said impeller and forces it outwardly through said outlet opening.
